UNITED STATES PATENT OFFICE.

ARTHUR J. WILLS, OF BROOKFIELD, MASSACHUSETTS; MABEL BARTON WILLS
EXECUTRIX OF SAID ARTHUR J. WILLS, DECEASED.

TRIMMER.

1,281,461.

Specification of Letters Patent. Patented Oct. 15, 1918.

Application filed March 9, 1915. Serial No. 13,106.

To all whom it may concern:

Be it known that I, ARTHUR J. WILLS, of Brookfield, in the county of Worcester and State of Massachusetts, a citizen of the United States, have invented a new and useful Improvement in Trimmers, of which the following is a specification.

My invention relates especially to a machine for trimming the overflow from rubber heels although it may be adapted for other like purposes such as the trimming of the overflow upon rubber soles, sink stoppers, matting and other articles. As my invention has been more particularly made for trimming rubber heels I will refer particularly to its use in such connection, but I do not mean to limit myself to this particular use.

In making rubber heels of the usual material the blank is first died out from a sheet of rubber compound and is placed in a mold of the desired shape and submitted to pressure during the vulcanizing process. The blank contains a slight surplus of the compound in order to insure the filling of the mold, and the heat necessary for vulcanizing liquefies the rubber compound to the extent that there is an overflow of the surplus around the edge where the top and body of the mold join. After the vulcanizing process has ceased this overflow is found to be attached to the heel or other article as a fin and must be removed before the heel is salable.

A cutter to trim heels or other vulcanized articles requires adjustment both to the lap of the blades, for the wearing of the cutters, and also to allow for the adjustment of the angle of the feed table to the cutters and to adjust the height of the cutters to the table in cases where the bottom of the article has projections which raise it and the fin above the level of the table. In other words, in a machine of this character there must be quite a wide range of adjustment of the blades in relation to the table in order to secure the best results and my invention comprises the embodiment of these and other points not heretofore combined so far as I am aware.

My invention will be understood by reference to the drawings in which it is shown in the best form of embodiment now known

to me, the machine shown being especially adapted for trimming heels.

Figure 1 is a plan and

Fig. 2 is a front elevation of such a machine.

Fig. 3 is an end elevation and

Figs. 4 and 5 are sections on lines 4-4 and 5-5 of Fig. 1.

A is the base or table upon which the various parts are mounted. A fixed shaft B is held by set screws *b* in uprights *B*¹ mounted on the table A and free to turn on this shaft is a triple pulley C, this pulley being kept from endwise movement between collars *c* which are attached to the shaft by screws *c*¹. The center groove of the pulley C is provided with a belt (not shown) by which power is applied to run the cutters. The cutters are lettered *d* and *e* and are mounted on the ends of shafts D and E, respectively. These shafts D and E are mounted in swinging frames. The frame carrying the shaft D comprises arms *D*¹ and crossbars *D*². The frame carrying the shaft E is similar in character having arms *E*¹ located below the crossbars *D*². Each of these frames is mounted to swing on the shaft B.

On the shaft D is mounted a pulley *d*¹ around which and the groove *d*² on the triple pulley C runs the cross belt *d*². On the shaft E there is also a pulley *e*¹ around which and the groove *e*² on the triple pulley C runs the belt *e*² so that power applied to the pulley C will cause the rotation of the shafts D and E and consequently of the cutters *d* and *e* in opposite directions. The frames carrying the shafts D and E are adjustable with relation to each other so as to adjust the cutting edges of the cutters with relation to each other. These cutters overlap as shown in Figs. 2, 4 and 5, the upper cutter being preferably the one nearer the work, and it is desirable that the amount of overlap may be regulated. For this purpose I provide two bars, one *d*⁴ connecting the crossbars *D*² and the other *e*⁴ connecting the crossbars *E*². Between each bar *d*⁴, *e*⁴ and one of the arms *D*¹, *E*¹ is pivoted a bar *f*, *f*¹ so that these bars may have a slight rocking movement as required.

Through threaded openings in the cross-

bars f , f' passes a right and left handed screw F (see Fig. 4), by turning which the frames carrying the shafts D and E are caused to approach or are moved away from each other according to the adjustment desired, the crossbars f , f' remaining in parallel relation during this adjustment.

The machine so far described includes the rotary mechanism whereby the cutters are given a proper rotation for cutting purposes and the adjusting mechanism whereby the overlap of the cutters is provided for. To adjust the engagement of the faces of the cutters, that is to say, to adjust the longitudinal position of the shafts carrying them so that the faces of the cutters will be always in contact, I preferably provide an upright G having a slot g which is curved, its curve being concentric with the shaft B . The cutters when in action are inclined to separate from each other, the upper or outer cutter tending to move outward and the under or inner cutter tending to move inward. To keep them in proper relation and at the same time to adjust their relative position I provide the shaft D at its outer end outside of the slotted upright G with a washer d^s and nut d^s which screws onto the threaded end of the shaft D , which end is reduced somewhat in diameter so that it may readily pass through the groove g in the upright G . The location of this nut and washer prevents the cutter d from moving outwardly or separating from the other cutter e . The shaft E at its outer end is also reduced somewhat in diameter where it passes through the slot g and it is provided with a washer e^s and nut e^s , this washer and nut, however, being on the opposite or inner side of the upright G so that the cutter e is prevented from moving rearwardly and so separating from the cutter d . The upright may be omitted, in which case the nuts and washers d^s , d^s and e^s , e^s may bear on one of the arms D , E .

The frames carrying the shafts D and E may be adjusted together about the shaft B in order to raise or lower the cutting edges of the cutters d and e with relation to the work table. For this purpose I provide two adjustments, one a permanent adjustment, which I will now describe, and the other a temporary adjustment to be used during the process of the work, which will be described below in connection with the work table. For the purposes of the permanent adjustment one of the arms E^1 carrying the shaft E is provided with a lug e' through which passes a screw H . The lower end of this screw rests upon a spring H^1 attached at one end to a bridge piece h which spans ways h^1 mounted at a proper level above the table A . The free end of said spring rests upon a sliding wedge piece H^2 , this piece running in the ways h^1 . It will be seen that

by turning this screw H in either direction the cutter supports or frames will be raised or lowered as occasion may require.

The work support J is mounted to swing in uprights j carried by the frame J^1 . The work support may be used either in horizontal or angular position.

The frame J^1 is adjustable on the table A , being slotted as at j^1 at various points and through these slots bolts j^2 having washers j^3 under their heads pass into the table A so as to clamp the frame thereto. I prefer this construction because it enables the work support to be adjusted as to its position and also enables it to be entirely removed in case it is desired to change the cutters. In front of the cutters the table is preferably thinned as at j^4 . In order that the work support J may have but a limited swing I attach to its under side an arm J^2 and provide the frame J^1 on which it is mounted with stops J^3 , the arm J^2 being sufficiently long to engage either one of these stops as the table is swung.

To the under side of the work support J a handle K is pivoted to slide in a strap k . This handle K is connected by a connecting rod K^1 with an arm K^2 mounted on the end of the shaft K^3 journaled in one of the uprights B^1 and also in an upright K^4 mounted on the table. To this shaft K^3 is attached by a rod k^1 the wedge piece H^2 , this attachment being adjustable for convenience. The joint between the handle K and the connecting rod K^1 is preferably a universal joint as at k^2 so as to allow the connecting rod K^1 to be operated by the handle K , whatever the position of the table may be.

In practice, the position of the cutters with relation to each other is first adjusted by means of the screw F . The overlap of the cutters may be great or small according to the work to be done. Moreover, this adjustment is necessary because as the cutters have to be ground from time to time their diameter is reduced.

The next step is the adjustment of the cutting edges of the cutters, that is, of the shears as a whole, to the level of the work support, and this is accomplished by means of the screw H . These preliminaries having been attended to, the work is placed upon the work support and the work support held at the proper angle and the machine having been started up, the overlap or fin is cut from the heel (if a heel is to be trimmed), the heel being turned by the operator to present the various portions of its edge to the cutters.

It is well known that at the present time there is a type of rubber heel having a projection, usually a fibrous inset, from its face near its rounded edge so that the face is higher at one portion than at the other. In trimming such a heel it is necessary when

presenting the rounded edge of the heel to the cutters that the cutting edges of the cutters shall be raised slightly for a moment above the level of the work support in order 5 to engage and cut the overflow, which at this point will not rest upon the work support. For this purpose the handle K is moved to the right (see Fig. 1), thus driving the wedge H² underneath the spring H¹ and 10 thus through the instrumentality of the screw H lifting both cutters and their frames bodily to a point on a level with the overflow so that the overflow from the back of the heel may be trimmed off evenly and 15 properly. When this part of the heel has been trimmed and the side edge of the heel is again reached, the handle is pulled to the left, thus returning the cutters to their normal position.

20 Thus it will be seen that provision is made by my invention for a heel trimmer in which the cutters having an adjustment with relation to each other and the cutting mechanism as a whole, have a permanent adjustment 25 with relation to the work support and also the capability of a temporary adjustment in order to meet requirements which arise during the cutting of an individual article. The end thrust on the cutters is 30 also provided for. It is also evident that these adjustments may be made in various ways, for which reason I do not mean to limit myself to the precise form of adjustments shown as other means of accomplishing the desired results will occur to those skilled in the art. Moreover, in the drawings a machine is shown which is especially 35 adapted for trimming heels although it may be used for trimming other similar articles.

40 By slight changes in design as well as changes in dimensions the principles of the machine may be embodied to do other like work. For example, two of these machines, properly proportioned, mounted opposite 45 each other, may be used for trimming simultaneously the opposite edges of a piece of matting. When cutting some rubber compounds the cutters and work should be kept wet as will be understood by those skilled 50 in the art.

The shape and mounting of the work support may be varied according to the requirements of the work. Other forms of work support are well known in the art and 55 may be substituted for that shown although the work support shown is the best for most purposes in rubber work. The edge of the work support nearest the cutters should be in line with the axis on which the work support turns.

In practice I prefer that the work support should be capable of vertical adjustment and for this purpose I have shown the uprights j as threaded and each is provided 60 with a nut j⁵ on which rests a bearing block

j⁶. The upper end of each upright is slotted at j and in each slot rests one axle j⁷ of the work support which is thus adjustably supported by the block j⁶ and nut j⁵.

What I claim as my invention is:—

1. A machine of the kind described comprising an axis and support therefor, two frames mounted to rock on said axis, one being located above the other, two coöperating rotary cutters, each mounted to rotate in one of said frames, means for rotating them, and means whereby said frames are adjusted with relation to each other whereby the relation of the edges of said cutters may be adjusted.

2. A machine of the kind described comprising an axis and means for supporting it, two frames mounted to rock on said axis, two coöperating, overlapping rotary cutters each rotatably mounted on one of said frames, means whereby they are rotated, and means whereby the amount of overlap of said cutters may be adjusted to adjust the positions of their cutting edges with relation to each other.

3. A machine of the kind described comprising an axis and means for supporting it, two frames mounted to rock on said axis, two coöperating, overlapping rotary cutters each rotatably mounted on one of said frames, means whereby they are rotated, means whereby the amount of overlap of said cutters may be adjusted to adjust the positions of their cutting edges with relation to each other, said means comprising a screw passing through both of said frames and adapted when turned to cause said frames and said cutters to approach or recede from each other.

4. A machine of the kind described comprising an axis and means for supporting it, rocking frames mounted on said axis, shafts, one carried in each of said rocking frames, two cutters one mounted on each shaft, said cutters overlapping, and means whereby said cutters will make a shear cut, comprising a stationary support for the end of each shaft opposite to that carrying the cutter, and nuts mounted on said shafts and in engagement with said support, the nut on the shaft carrying the outside cutter bearing on the outside of said support and the nut on the other shaft bearing on the inside of the support whereby the screwing of either of said nuts in the direction of the support will cause the approach of the said cutters.

5. A machine of the kind described comprising a support, an axle mounted therein, two frames mounted to rock on said axle, two shafts each mounted parallel to said axle in one of said frames, cutters mounted on adjacent ends of each shaft, said cutters overlapping each other, and means for holding said cutters in overlapping engagement comprising a slotted stationary member,

4

5 said shafts passing through the slot in said member, and nuts mounted one on the end of each shaft, the nut on the shaft carrying the outside cutter bearing against the outside of 5 the stationary member whereby it may adjust the outside cutter against the inside cutter and the nut on the shaft carrying the inside cutter bearing against the inside of the stationary member, whereby it may adjust 10 the inside cutter against the outside member.

6. A machine of the kind described comprising a fixed shaft, two frames mounted to rock together thereon, a rotary shaft mounted in each frame, a cutter mounted on one end 15 of each rotary shaft, said cutters overlapping to engage the work at the same point, an adjustable work support adjacent to said cutters, and means to adjust the relation of said cutters to each other, and means to adjust 20 the cutters with relation to the work support.

7. A machine of the kind described comprising a fixed shaft, two frames mounted to rock together thereon, a rotary shaft 25 mounted in each frame, a cutter mounted on one end of each rotary shaft, said cutters overlapping to engage the work at the same point, a work support adjacent to said cutters, and means to adjust the height of said 30 cutters with relation to said work support, said means comprising a screw passing through said frame and means to engage the lower end of said screw whereby the turning of said screw will raise or lower 35 said frames about said stationary shaft.

8. A machine of the kind described comprising a fixed shaft, two frames mounted to rock together thereon, a rotary shaft mounted in each frame, a cutter mounted 40 on one end of each rotary shaft, said cutters overlapping to engage the work at the same point, a work support adjacent to said cutters, and means to adjust the height of said 45 cutters with relation to said work support, said means comprising a screw passing through said frame and means to engage the

lower end of said screw whereby the turning of said screw will raise or lower said frames about said stationary shaft, said last-named means comprising a wedge and means for 50 moving it to adjust the height of the point of its engagement with said screw.

9. A machine of the kind described comprising a fixed shaft, two frames mounted to rock together thereon, a rotary shaft 55 mounted in each frame, a cutter mounted on each rotary shaft, said cutters overlapping to engage the work at the same point, a work support adjacent to said cutters, and means to adjust the height of said cutters 60 with relation to said work support comprising a wedge, ways therefore, a support mounted on said frame and resting on said wedge, and means for moving said wedge to raise and lower said support comprising a 65 handle lever pivoted on said work support and connections between said handle lever and said wedge.

10. In a machine of the kind described, in combination with a cutting mechanism, a 70 work support and means for supporting it comprising threaded uprights, a nut on each upright, a block resting on said nut, the upper end of each upright being slotted and the work support being provided with axles 75 resting in said slots and on said blocks.

11. In a machine of the kind described, a base, an axle mounted thereon, rocking frames mounted on said axle, means for adjusting the angle of said rocking frames to 80 each other, shafts mounted on said frames, a cutter mounted on each shaft, means for rotating said cutters, a work support one edge of which is in close proximity to said cutters, and means for adjusting the height 85 of the cutters with relation to the adjacent edge of said work support.

ARTHUR J. WILLS.
